PROCESS OF AND MEANS FOR MAKING MATCHES

Filed Aug. 2, 1929

UNITED STATES PATENT OFFICE

WALTER O. AUGUSTINE, OF RAHWAY, NEW JERSEY, ASSIGNOR TO THE DIAMOND MATCH COMPANY, OF CHICAGO, ILLINOIS, A CORPORATION OF ILLINOIS

PROCESS OF AND MEANS FOR MAKING MATCHES

Application filed August 2, 1929. Serial No. 383,054.

This invention relates to a process of and means for making matches having splints of permeable combustible material; its object being to provide for the economical and efficient treatment of the splints with a material, such as ammonium phosphate, which is effective to limit the flame to a relatively small portion of the splint when a match is ignited, and which material is also effective to prevent the glowing of the burnt or charred part of the splint when the flame is extinguished.

The invention is especially designed for use in connection with a match making machine of the class wherein the splints are inserted endwise, row by row, in an endless carrier and thereby rigidly held in spaced parallel relation and transported through the match making path, including wax (as paraffin) and head composition applying mecha-

In carrying out the invention in the preferred way the projecting match splints, supported in spaced parallel relation by the carrier, are impregnated with a fire-resisting solution, such as ammonium phosphate of sufficient concentration to impart the requisite fire-resisting characteristic to the splints. The concentrated impregnating material, in the free end portions of the splints, to an extent substantially corresponding with the desired inflammable area of the splints, is reduced by a solvent to a condition which permits the burning of the splints, when dried, yet prevents their glowing when the flame is extinguished.

The splints thus treated travel through a suitable drying zone, and their free impregnated end portions, when dry, are dipped to a suitable depth into molten wax, as paraffin. The splints are then exposed to the atmosphere for a brief interval to allow the wax to set, whereupon the free extremities of the splints are tipped with ignitable composition or compositions to form the match heads. The matches thus produced are conveyed through a suitable drying space, whence they are discharged from the carrier and packed.

Figures 1 and 2 of the drawings are illustrative diagrams of parts of a match making machine designed to carry out my herein-

before described process. In the drawings, 3 designates a portion of an endless carrier in which match splints, 4, are endwise inserted, row by row, and thereby rigidly held in spaced parallel relation.

5 designates a suitably-located sprayer whereby a free flowing fire-resisting material, such as a highly concentrated solution of ammonium phosphate, is projected upon and longitudinally of the splints.

6 designates a bath of water through which pass, to a predetermined depth, the lower ends of the depending impregnated splints during the progress of the carrier. The water is caused to flow to and from the bath and is maintained at a certain level, the period of travel of the splints therein being such as to reduce the concentrated impregnating material to the proper condition, as previously mentioned.

7 designates a drying chamber through which progress the impregnated splints after they leave the water bath, passing thence to and along a bath 8 of molten paraffin, or the like, in which the lower ends of the depending splints are immersed to a depth corresponding with the desired inflammable area of the splints.

9 designates a composition containing vat equipped with a transfer roll 10 by means of which head composition is applied to the lower paraffined ends of the depending splints during the travel of the carrier.

Instead of spraying the splints with the impregnating solution, the splints may be 85 dipped in a suitable bath (50) containing the solution, as seen in Fig. 2.

I claim:

1. A process of making matches, comprising impregnating a splint with a fire-resisting solution, reducing, by a solvent, the concentration of the solution in the free end portion of the splint to a depth substantially corresponding with the desired inflammable area of the splint, then drying the splint, 95 then treating the reduced impregnated portion of the splint with wax, then applying head composition to the free end of the waxed portion of the splint.

2. In a process of making matches, the 100

steps of impregnating a splint with a fire-resistant solution, and reducing, by a solvent, the concentration of the solution in the free end portion of the splint to a depth substantially corresponding with the desired inflammable area of the splint.

3. In a match machine, the combination with a carrier for match splints, of means for impregnating the splints with a fire-resistant solution, and means for reducing, by a solvent, the concentration of the solution in the free ends of the splints to a depth substantially corresponding with the desired inflammable area of the splints.

15 4. In a match machine, the combination with a carrier for match splints, of means for impregnating the splints with a fire-resistant solution, and means for reducing the concentration of the solution in the free ends of 20 the splints to a depth substantially corresponding with the desired inflammable area of the splints, said last named means including a bath of flowing water through which are caused to pass the lower impregnated portions of the splints.

25 5. In a match machine, the combination with a carrier for match splints, of means for impregnating the splints with a fire-resistant solution, means for reducing, by a solvent, 30 the concentration of the solution in the free ends of the splints to a depth substantially corresponding with the desired inflammable area of the splints, means for drying the impregnated splints, means for treating the reduced impregnated portions of the splints 35 with wax, and means for applying head composition to the free ends of the waxed portions of the splints.

Signed at New York in the county and
40 State of New York this 1st day of August,
A. D. 1929.

WALTER O. AUGUSTINE.
